UNITED STATES PATENT OFFICE.

GEORGE T. STRITE, OF MINNEAPOLIS, MINNESOTA, ASSIGNOR OF ONE-HALF TO H. W. BOLENS AND ONE-FOURTH TO CHARLES J. TRAVERS, BOTH OF PORT WASHINGTON, WISCONSIN.

FAN GOVERNOR FOR THRASHING MACHINES.

1,406,427.

Specification of Letters Patent. Patented Feb. 14, 1922.

Application filed March 21, 1919. Serial No. 284,114.

To all whom it may concern:

Be it known that I, GEORGE T. STRITE, a citizen of the United States, residing at Minneapolis, in the county of Hennepin and

5 State of Minnesota, have invented certain new and useful Improvements in Fan Governors for Thrashing Machines, of which the following is a specification.

My invention relates to fan governors for 10 thrashing machines and an object is to provide means whereby it will be impossible to speed up the fan beyond a predetermined amount. While my governor or regulating device may be employed in connection with 15 fans used in other relations such as fanning mills, it is intended particularly for use in connection with thrashing machines. In the operation of thrashing machines, when the bundles which are being fed in get past 20 the cylinders the machine immediately speeds up before it is slowed down by succeeding bundles. The result is that the fan is speeded up to an excessive degree and some of the grain is blown over by the strong 25 blast of air which is produced and escapes with the chaff and straw. The loss of grain in this manner is very considerable and, therefore, an object of my invention is to provide a device which will maintain a constant 30 speed for the fan regardless of the speed at which power to operate the fan is applied. By maintaining a constant speed of the fan the force of the air blast is always at a constant pressure, and by setting the 35 device so that the fan shall never exceed a predetermined speed the waste of grain by blowing over is prevented. Another object of my invention is to construct the governor so that it may be readily adjusted to 40 run the fan at any desired constant speed. This adjustment is desirable, especially for different grains.

The full objects and advantages of my invention will appear in connection with the 45 detailed description, and the novel features embodied in my inventive idea will be particularly pointed out in the claims.

Referring to the accompanying drawings, which illustrate the application of my invention in one form,—

Fig. 1 is a side elevational view of a 50 thrashing machine showing the location of the fan to which my invention is applied. Fig. 2 is an end view of my governor. Fig. 55 3 is an enlarged view mainly in section of

my device applied at one end of a fan. Fig. 4 is a view in section on the line 4—4 of Fig. 2 showing the arrangement of spokes of the brake drum.

Referring to the particular construction 60 shown in the drawings, 10 designates a thrashing machine of usual or desired construction provided with a fan shaft 12 driven in any suitable manner by driving connections operated by the same prime 65 mover that operates the rotating cylinders of the machine. Since the fan may be of any usual construction it is not considered necessary to illustrate and describe the same in detail and hence only the end thereof to 70 which my device is applied is described. To the end of the shaft 12 is keyed the hub 14 of a drum having a rim 16 connected to the hub by spokes 18, the latter being preferably inclined to the plane of rotation of the 75 drum in order to force air through the customary side opening 20 leading into the fan chamber 22. The fan is provided with hubs 24 at each end thereof which are connected by a cylindrical member 26 surrounding but 80 preferably spaced from the shaft 12, the hubs being supported on bushings or bearings 28 interposed between the shaft and the hubs 24. These hubs are provided with a 85 number of radially-extending angle members 30 to which the supports 32 for the fan blades are secured by bolts 34. A pair of arms 36 are pivotally attached to two of the opposite angle members 30 by means of 90 pintles 38. Each of the arms 36 is provided with a block 40 of friction material, and these blocks engage the rim 16 in the manner of brake shoes. Each of the arms 36 at one side of the pintle is provided with a lug 42, the main portion of the arm extending on the other side of the pintle and terminating in a lug 44. Bolts 46 pass through 95 holes in the adjacent lugs 42 and 44 and these bolts are provided with springs 48 adjustably held in place between one of the lugs and collars 50 slidable on the bolts, the position of the collars being determined by nuts 52 threaded on the ends of the bolts.

The operation and advantages of my invention will be apparent from the foregoing 100 description. The fan shaft 12 is connected up so as to be driven normally at a higher speed than the speed at which it is desired to drive the fan. The governor is set to 105 drive the fan at a predetermined speed 110

which is considerably less than the normal speed of the fan shaft. The result of this is that not only is it impossible for the fan to speed up if the speed of the fan shaft exceeds its normal speed, but the speed of the fan shaft may fall considerably below its normal speed without the speed of the fan decreasing. This latter result is important since some of the grain will go over with the chaff if the speed of the fan falls below its proper predetermined speed. When the fan shaft is running at normal speed there is always relative slipping between the rim 16 and the friction blocks 40, the amount of this slipping being predetermined by the tension under which the springs 40 are placed by turning the nuts 52, and when the speed of the fan shaft falls below normal the amount of this slipping becomes less. The governor, therefore, may be set so that the fan shall run at a constant speed which may be varied according to the character of the grain which is being put through the machine.

25 In the operation of my regulating device the fan shaft 12 may be conveniently driven from the cylinder of the thrashing machine by a belt 54 running over a pulley 56 secured to the cylinder shaft and a pulley 58 secured to the fan shaft in the usual manner. As previously stated, the regulating device is set so that the fan is run at a predetermined speed which is considerably less than the normal speed at which I drive the fan shaft. It is obvious that the fan shaft may be caused to run faster under normal conditions than is customary at present by varying the size of the pulleys over which the belt 54 runs. In connection with the operation of the device, it is to be noted that the friction members attached to the fan operate centrifugally against the tension of the restraining springs. The latter are so set that the centrifugal force will cause the friction members to move outwardly from the drum and allow slipping as soon as the fan attains its normal speed, this being considerably less than the normal speed at which the fan shaft is driven. It is apparent, therefore, that the speed of the fan shaft may fall to that of the normal speed of the fan without the speed of the fan falling.

I claim:

- 55 1. A fan governor for thrashing machines comprising a fan shaft, and means interposed between the said shaft and the fan for driving the latter at a constant speed as the speed of said shaft varies above a predetermined lower limit of speed.
- 60 2. A fan governor for thrashing machines comprising a fan shaft, frictional connections between said shaft and the fan, and

means for setting said connections so that they will slip when the fan shaft is running at normal speed.

3. A fan governor for thrashing machines comprising a fan shaft, frictional connections between said shaft and the fan, and means for setting said connections so that they will slip when the fan shaft is running at normal speed and the amount of slipping will decrease as the speed of the fan shaft falls below normal.

4. A fan governor for thrashing machines comprising a fan shaft, a friction drum secured to said shaft, and friction members secured to the fan for cooperation with said drum whereby the speed of the fan is maintained constant as the speed of the fan shaft varies above a predetermined lower limit of speed.

5. A fan governor for thrashing machines comprising a fan shaft, a friction drum secured to said shaft, friction members secured to the fan for cooperation with said drum, and means for varying the frictional resistance between said drum and said members.

6. A fan governor for thrashing machines comprising a fan shaft, a friction drum secured to said shaft, arms pivotally attached to the fan, friction members carried by said arms for cooperation with said drum, springs for holding said members in contact with said drum, and means for varying the tension of said springs.

7. A fan governor for thrashing machines comprising a fan shaft, frictional connections between said shaft and the fan, and means for setting said connections so that they will slip when the fan shaft is running at normal speed and the amount of slipping will increase as the speed of the fan shaft increases above normal.

8. A fan governor for thrashing machines comprising a fan shaft, means interposed between said shaft and the fan for driving the latter at a constant speed as the speed of said shaft varies above a predetermined lower limit of speed, and means whereby the constant speed may be varied as desired.

9. A thrashing machine comprising a cylinder, a fan, means for driving said fan from said cylinder, frictional connections between said fan and the fan shaft, and means for setting said connections so that they will slip the proper amount to maintain the speed of the fan constant as the speed of the fan shaft and cylinder varies above a predetermined lower limit of speed.

In testimony whereof I hereunto affix my signature.

GEORGE T. STRITE.
